UNITED STATES PATENT OFFICE.

JONATHAN HARRIS, OF CLEVELAND, OHIO.

SCREEN-BRUSH.

SPECIFICATION forming part of Letters Patent No. 783,266, dated February 21, 1905.

Application filed October 15, 1904. Serial No. 228,527.

To all whom it may concern:

Be it known that I, JONATHAN HARRIS, a citizen of the United States, and a resident of Cleveland, county of Cuyahoga, State of Ohio, 5 have invented certain new and useful Improvements in Screen-Brushes, of which I hereby declare the following to be a full, clear, and exact description, such as will enable others skilled in the art to which it appertains to make 10 and use the same.

The invention has reference to traveling brushes for cleansing the wire screens in a seed-cleaning or other analogous device; and the 15 objects of the invention are to provide means for obtaining increased efficiency and practicability in the action of the brushes, and thereby more perfectly cleanse the screen of refuse matters collected in the openings thereof, so that they may be discharged into the proper 20 receptacles.

The invention consists in longitudinally-traveling brushes in lieu of the transversely-traveling brushes heretofore employed and in the various details of construction and arrangement of parts, as hereinafter described, 25 shown in the accompanying drawings, and specifically pointed out in the claim.

In the accompanying drawings, Figure 1 is a side elevation of a seed-cleaning device, 30 partly broken away to show the screens and traveling brushes in their relative positions therein. Fig. 2 is an enlarged transverse section through one of the screens, showing the position of one of the brushes and the longitudinal bars of the screen. Fig. 3 is an end elevation of a brush, showing a portion of supporting sprocket-chain and the driving sprocket-wheel therefor. Fig. 4 is an enlarged 35 view of the end of one of the brushes, showing the sprocket-chain in section. Fig. 5 is a perspective view of the bottom of one of the screens. Fig. 6 is a perspective view of one of the brushes.

In the views, 1 and 2 are the screens resting 45 in grooves in the reciprocating shoe 3.

4 4 are transverse bars for these screens, and 5 5 are longitudinal bars which strengthen and stiffen the screens.

6 is the perforated plate forming the screen. 50 7 7 are sprocket-wheels over which pass end-

less chains 8, upon which the brushes 9 are secured at regular intervals. These chains are made to follow the incline of each screen and are strictly parallel therewith. They move from the lower end of each screen over the 55 lower surface thereof and pass to the upper end, thus removing any matters which have lodged in the holes 10 of the screen.

Shafts 11 serve to support the sprockets 7 7, and the shafts are driven by means of bands 60 12 (shown in dotted lines) on the outside of the machine, which pass over pulleys 14 on the main shaft 15 of the machine.

Where the brushes would, if continuous, engage with the longitudinal bars 5 of the screens, 65 they are cut away, as at 13, but are adapted to make close contact with the surface of the screen wherever exposed.

The advantages of this method of cleansing the openings in the screens from matters deposited therein is as follows: Heretofore traveling brushes have acted transversely across the surfaces of the screens. Particles of refuse material or grain, however, falling into the openings, as *a*, Fig. 3, in the inclined 70 screens will lodge against the lower edges of the openings, and hence the use of a brush transversely across the surface of the screen 75 will have very little efficiency in removing the same if tightly lodged; but a brush acting longitudinally of the screen and brushing upwardly over the surface will act upon the particles at the very parts which are lodged and in the direction from which they entered the holes. Thus they can readily be removed. 80

In Fig. 3 is shown a device whereby the brushes 9 can be raised to offset their reduction in length from wear upon the screen 6. This device is exceedingly simple and efficient 85 and comprises a bar 16 underneath the upper 90 side of the brush-conveyer, upon which the particular links which support the brushes travel. These bars are adjustably supported upon the sides of the shoe 3 by means of pins or bolts 17, which pass through diagonal slots 95 18 in the bars. As many of these pins and slots are employed as may be deemed necessary to support the brushes. A knob 19 in one end of the bar 16 is used as a handle to move it longitudinally on the pins, the sides 100

of the diagonal slots giving a vertical movement thereto. The links to which the brushes are attached are provided each with a heel 20, which rides directly upon the bar 16 and from 5 its position in the rear of the link keeps the brush upright under the frictional strain of contact with the screen.

Having described my invention, what I claim as new, and desire to secure by Letters 10 Patent, is—

The combination with the shoe and screen of a seed-cleaning machine, of endless-chain conveyers mounted longitudinally of the screens thereunder, transverse brushes upon

links of said conveyer, a heel at the rear end 15 of each of such links, bars underneath the upper side of each conveyer upon which said heels are arranged to travel and pins in the sides of the said shoe, and diagonal slots in the said bars through which said pins pass, 20 whereby vertical adjustment is given to the said bars, substantially as described.

In testimony whereof I hereunto set my hand this 18th day of July, 1904.

JONATHAN HARRIS.
